UNITED STATES PATENT OFFICE.

JEAN ROMEYN, OF ST. GILLES, NEAR BRUSSELS, BELGIUM.

CENTRIFUGAL GOVERNOR.

Application filed January 9, 1923. Serial No. 611,661.

To all whom it may concern:

Be it known that I, JEAN ROMEYN, a subject of the Queen of Netherlands, and resident of St. Gilles, near Brussels, Belgium, have invented certain new and useful Improvements in Centrifugal Governors; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

The present invention relates to centrifugal governors of the kind in which the action exerted by a spring or by springs is opposed to the centrifugal forces, and especially to those which can be adapted to operate at different speeds by altering, while running, the tension of the spring or springs.

According to the invention, the springs are arranged parallel to the governor shaft or nearly so, and have one of their ends attached to a part to which a sliding displacement along the shaft can be imparted, in order to change the speed at which the governor works; the other end of each spring is attached to a lever which is pivoted on a knife edge, and at such a point that the elementary variation of the length of the spring corresponding to a given elementary radial displacement of the centrifugal masses increases continuously when the governor opens; the lever just referred to transmits the action of the spring to one of the centrifugal masses which are supported by separate levers.

In order that the advantages of the present invention may be better understood, it will be advisable to present in a suitable form the general theory of operation of governors of this class.

Figures 1, 2 and 3 of the accompanying drawings refer to the general theory, whereas Figs. 4, 5, 6 and 7, which will be explained later on, are applicable to the subject of the present invention.

Let us consider a spring governor, the

shaft of which will be supposed to be vertical, in order to simplify the explanation. We will further suppose that each centrifugal mass is pivoted on a horizontal pivot and moves in a radial plane.

The lever which bears each centrifugal mass is subjected to several moments, which can be reduced when neglecting friction, to the following four:

(1) A moment created by the centrifugal force of the mass;

(2) A moment produced by the centrifugal forces acting upon each portion of the governor connected to the considered mass;

(3) A moment created by the tension of the springs, acting directly or not, upon the centrifugal mass;

(4) A moment produced by gravity acting upon each portion connected to the mass.

For each position of the mass, the four moments hereabove can be replaced by four horizontal and radial forces applied to the centre of gravity of the mass, and having the same effect.

We will designate the centrifugal force of the mass by C , the force corresponding to the centrifugal forces of all parts connected therewith by c , the force corresponding to the action of the spring by S , and the force produced by the action of gravity on each portion connected to the mass by W .

These forces will be considered as positive when acting outwards.

We will further designate by r the minimum distance from the centre of gravity of the mass to the centre-line of the shaft, by R the same distance, when at a maximum, by w_0 the minimum angular speed and by w_1 the maximum angular speed between which the governor is designed to work.

Let us consider, with a constant angular speed equal to w_0 the different positions of the mass, between the distances corresponding to r and R . When tracing (Fig. 1) a diagram of the centrifugal force C , we will have of course a straight line AB the prolongation of which goes through O .

Supposing we add to the ordinates of the diagram AB the corresponding values of c , we will have a curve $A'B'$. The force c is generally small as compared with C and its variation is not far from linear. Therefore, we can replace the curve $A'B'$ by the straight line $A'B'O'$ without any appreciable error.

Supposing now the governor rotates at a new constant angular speed w_2 all ordinates of the diagram above referred to will be multiplied with the same ratio

$$15 \quad \left(\frac{w_2}{w_0}\right)^2$$

so that the new diagram of $C+c$ will be illustrated by another line (for instance $A''B''$) cutting the abscissa at the same point O .

When plotting in the diagram of Fig. 1, the curve of $-(S+W)$ we will obtain a curve such as $A'C$ having its initial point superposed on the initial point of the curve representing $C+c$ and its final point higher than the final point of the curve $C+c$: the reason for this is that the state of equilibrium is attained at the speed w_0 corresponding to the diagram $A'B'$ when the distance from the centre of gravity of the mass to the shaft centre line is r , while equilibrium is attained at the speed $w_1 > w_0$ when the said distance is equal to R .

Furthermore we must have

$$35 \quad \frac{CE}{B'E} = \left(\frac{w_1}{w_0}\right)^2$$

Once more we will make an error of minor importance if we replace the curve $A'C$ by the straight line $A'C$, cutting OE at the point F .

Suppose the tension of the spring or springs to be altered in order to render the equilibrium speed corresponding to the minimum distance r equal to w_2 , a new diagram of $-(S+W)$ such as $A''C'$, will be obtained (supposed again to be straight) having its initial point superposed on the initial point of the diagram $A''B''$ (corresponding to the constant speed w_2). If w_3 is the maximum angular speed of equilibrium for the governor thus altered,

$$45 \quad \frac{C'E}{B''E} = \left(\frac{w_3}{w_2}\right)^2$$

is again true.

The condition for obtaining the same coefficient of irregularity as before when reducing the speed as considered here above, will read

$$60 \quad \frac{w_3}{w_2} = \frac{w_1}{w_0} \text{ whence } \frac{C'E}{B''E} = \frac{CE}{B'E}$$

It will be now shown that this condition is fulfilled only when the point F' falls on the point F .

Therefore a straight line FGH may be drawn parallel to $O'A'B'$ and

$$55 \quad \frac{O'F}{FD} = \frac{A'G}{GD} = \frac{CH}{HE} = \frac{CB'}{CB} \times \frac{B'E}{B'E} \times \frac{CH}{HE} = \\ \frac{CB'}{B'E} \times \frac{CH}{HE} \times \frac{CB'}{CB} = \frac{O'E}{B'E} \times \frac{FH}{FE} \times \frac{A'B'}{A'B} = \\ \frac{CB'}{B'E} \times \frac{O'E}{FE} = \frac{CB'}{B'E} \times \frac{O'E}{DE} = \frac{B'E}{B'E} \times \frac{DE}{DE}$$

also

$$\frac{O'F'}{F'D} = \frac{C'B''}{B'E} \times \frac{O'E}{DE}.$$

Consequently if it is proposed to render $\frac{C'E}{B'E}$ equal to $\frac{CE}{B'E}$ or $\frac{C'B''}{B'E}$ equal to $\frac{CB'}{B'E}$ then $\frac{O'F'}{F'D} = \frac{O'E}{FD}$.

If the variable force which the spring exerts upon the movable part to which it is attached be replaced by a constant force f and for each position of the mass the horizontal force F having the same effect as the moment developed by f be calculated, a diagram such as JK Fig. 2 will be obtained for $-F$ the ordinates of which are proportional to the chosen force f . Consequently if the curve JK be replaced by the straight line JKL (which generally can be done without any appreciable error) it can be said that the position of the point L is constant whatever the force f may be, and depends only upon the dimensions of the connecting parts through which the action of the force f is transmitted to the mass.

Let us now trace (Fig. 3) the actual diagram MN of the force $-S$ corresponding to the spring and also the diagram $A'C$ of $-(S+W)$ corresponding to the combined action of spring and gravity. These two diagrams may be supposed as an approximation to be straight lines. On drawing through the point P (whether or not it falls between the ordinates corresponding to r and R) the straight line PL (the point L being the same as in Fig. 2), the diagram $J'K'L$ can be considered as representing a force applied horizontally to the mass and corresponding to a constant force f' of convenient value acting upon the mechanism instead of the spring. Consequently the ordinates between the lines $J'K'$ and MN correspond likewise to the action of the different positive and negative forces which have to be added to the constant force f' in order to obtain the different actual forces of the spring in the various positions considered.

If the governor is so designed that the speed can be altered without varying the coefficient of irregularity, by altering the tension of the spring or springs, for a second working speed a diagram of $-(S+W)$ such as $FA''C'$ will be obtained (Fig. 3) going through the point F , as has been demonstrated above.

As the action of gravity always remains the same, the diagram of $-S$, will go through the points M' and N' the distances $M'A''$ and $N'C'$ being equal to MA' and NC respectively. Consequently the points P' and P will fall on the same ordinate. When drawing the straight line $P'L$, the diagram $J''K''$ will represent the action upon the mass of a constant force equal to the actual force of the spring for the position corresponding to the point P' and acting upon the mechanism instead of the spring.

If we consider only the case of helical springs the number of coils of which is constant, the variation of the force, when passing from a given position of the movable spring end corresponding to the points P and P' to any other position, is independent of the actual force of the spring in the initial position. Therefore the distances $M'J''$ and $N'K''$ must be respectively equal to MJ' and NK' .

As the ordinates between the diagram $M'N'$ and $A''C'$ are equal to the corresponding ordinates between MN and $A'C$ and furthermore as the ordinates between $A''C'$, and $J''K''$ are equal to those between $A'C$

and $J'K'$ multiplied by $\frac{P'Q}{PQ}$ the condition

just above expressed cannot be fulfilled unless the point L falls on the point F . Hence the following two rules may be enunciated:

When it is proposed to obtain a constant degree of irregularity at various speeds with a spring governor by altering the tension of the spring or springs without changing the stiffness of the spring or springs, nor the relation between the elementary variation of the length of the spring or springs and the elementary displacement of the masses in the different positions:

(1) The governor must be so designed, that at a given working speed, but taking into account the degree of irregularity to be obtained, the action of all centrifugal forces can be balanced by a constant force acting in place of each spring.

(2) The stiffness of the spring or springs must be such that the action of gravity applied to all movable parts is exactly balanced by the variable force which must be added to or subtracted from the constant force just referred to in order to obtain the actual force of the spring or springs.

From these, a third rule may be deduced:

As the centrifugal force carries out a motive work when the distance between the mass and the shaft increases, this work is finally transmitted to the spring. Consequently its length must increase, and also the force it develops. Thus the diagram of $-S$ must be more inclined with respect to the abscissa, than the diagram $A'C$ which

corresponds to the action of a constant force, according to the first rule.

As the forces represented by the ordinates between the diagram $A'C$ of $-(S+W)$ and the diagram MN of $-S$ must be balanced by the action of gravity (second rule) the diagram of $-W$ must be inclined as shown in Fig. 3 by the line ST , and the diagram of W as shown by $S'T'$.

Whence the third rule:

The governor must be so designed that the action of gravity is more opposed (or less favorable) to the action of the centrifugal force when the radius is at a minimum than when at its maximum.

In order that the invention may be better understood, Figs. 4, 5, 6 and 7 may be referred to which show by way of example a particular form of construction; and it is shown how the three rules above mentioned are applied thereto and how several further advantages are obtained.

Fig. 4 is an elevation of a governor according to the invention, Figs. 5, 6 and 7 are modified details thereof.

In Fig. 4, a is the rotating shaft of the governor. There are two masses or weights b , each of which is mounted on a bell crank lever c pivoted at d on a support e which is solid with or keyed on the shaft.

The sleeve f which transmits up and down motion to lever g supported by the rod h pivoted at i on a fixed part, does not rotate with the shaft; it is connected with the levers c by means of square blocks j , each of which is provided with a pin k engaged in the eye of the adjacent lever c . The blocks j slide in the circular groove l of the sleeve F .

The weights are round bodies and are free to rotate on their pins m .

The springs n are nearly parallel to the shaft. One of their ends is attached to the sleeve o , which is rotated by the shaft by means of a key p , but can be displaced up and down by means of the collar q , the lever r , the rod s , the screw t and the hand-wheel u .

Each spring acts upon a bell crank lever v pivoted at w on a knife edge and bearing against the corresponding weight at its flattened end x .

The pivot point d is situated below the weight and so the third rule above referred to is observed i. e., the action of gravity is opposed to a maximum degree to the action of centrifugal force.

The point at which the spring is connected with the lever v is situated below the fulcrum point w of the lever and nearer the shaft. It is easy to choose its position so that the distance y remains nearly proportional to the centrifugal force when the governor opens, and in this way the first rule can be observed, with a sufficiently close approximation.

Finally the stiffness of the springs (i. e. the number of their coils if the mean diameter and the size of the wire are known) will be determined by the second rule.

5 Aside from its simplicity, the governor described above is very advantageous as regards sensitiveness. No appreciable friction is developed at the points where knife edges are provided, nor at the points where 10 the weights roll against the ends *x* of the levers *v*. Moreover, as the sleeve *f* does not rotate with the shaft, the vertical component of the friction developed between both 15 parts is equal to the total friction multiplied by the ratio of the vertical speed of the sleeve to the total relative speed of the surfaces in contact. The sleeve thus acts just in the same manner as an oil brake: its action is very slight when the vertical movement 20 of the sleeve is very slow.

Furthermore, supposing the tension of the springs or the centrifugal forces to be unequal, the only result thereof is that there are additional reactions between the shaft 25 and the sleeve at both ends thereof, but it has just been explained that the friction resulting from such pressures cannot lessen the sensitiveness of the governor.

30 No special care is taken to avoid friction at the pivot points *m*, *d*, and *k*, but the forces acting upon these pivot pins are not important as compared with the centrifugal force: they are due to gravity only and to a small component of the force exerted by 35 the lever *v* upon the weight *b*, in the positions in which the surface of contact is not vertical.

If the tension of the different springs is 40 not equal, there would be an additional friction at the points *m*, *d*, and *k*, owing to the balancing force which would be transmitted from one mass to the other. Therefore, the mechanism can be improved by mounting 45 on the sleeve *o* a lever *z*, as shown in Fig. 5.

50 The governor described presents a further distinct advantage: In many cases the shaft upon which a governor is mounted is so designed as to fulfil other purposes (for instance to transmit the movement from the crank-shaft of an engine to the cam-shaft) and as a consequence thereof the said shaft cannot be dismantled easily as a whole. When the governor described is mounted upon such a shaft, the springs can be taken away and replaced without any difficulty, 55 which is not the case in the governors in which the spring or springs is or are mounted around the shaft.

60 Of course, it is also possible to observe the three rules above referred to when attaching directly the spring to the lever *c*, as shown in Fig. 6, and in this case the weight can be solid with the said lever. But for the sake of sensitiveness, it is then necessary 65 to employ a knife edge *d'* at the point *d*.

In this latter design, owing to the considerable weight of part *b*, *c*, and to the lateral clearance, which cannot be dispensed with at the point *d*, the angular accelerations to which the governor shaft may be subjected 70 will cause, in certain circumstances, a small sliding movement of the part *b*, *c*, along the edge of the knife, which might injure the said edge. In the case of Fig. 4, there can be no sliding movement of the lever *v*, because the inertia applied to this light part 75 will always be less than the lateral friction developed by the pressure on the knife edge. In the design of Fig. 6 it will be necessary 80 to prevent the said sliding movement at the edge of the knife, by allowing for a small sliding movement of the knife *d'* itself in the holes of part *e*, in which it is fitted.

Obviously, the number of weights is not limited: there can be 3, 4 or more weights 85 without departing from the scope of the invention.

The weights can also be connected with the sleeve *f* in the manner shown in Fig. 7, although this design is less satisfactory as regards friction; in this case the sleeve *f* 90 would rotate with the shaft, and be connected with the lever *g* by means of a sliding member. Finally the sliding parts *j* 95 can be replaced by rollers.

I claim as my invention:—

1. In a centrifugal governor, the combination, with a rotatable shaft, of a plurality of centrifugal weights; a carrier lever individual to each weight; a controlling sleeve movable along the shaft and connected with the levers; a set of helical springs, one for each weight, disposed approximately parallel with said shaft; a member freely adjustable on said shaft while the latter is rotating and with which one end of each spring is connected; and a set of bell-crank levers, one for each weight and bearing thereagainst at one end, each bell-crank 100 lever being fulcrumed intermediate its ends 105 on a knife-edge bearing and connected at its other end to the other end of the associated spring.

2. In a centrifugal governor, the combination, with a rotatable shaft, of a plurality of weight-carrying levers; a centrifugal weight individual to each lever and having the form of a round body pivotally supported at its center thereon; a controlling sleeve movable along the shaft and connected with said levers; a set of helical springs, one for each weight, disposed approximately parallel with said shaft; a member freely adjustable on said shaft while the latter is rotating and to which one end of each spring is connected; and a set of bell-crank levers, one for each weight, and bearing thereagainst at one end, each bell-crank lever being fulcrumed intermediate its ends 110 on a knife-edge bearing and connected at its 115 other end to the other end of the associated spring.

120

125

130

connected at its other end to the other end of the associated spring.

3. In a centrifugal governor, the combination with a rotatable shaft, of a plurality of centrifugal weights; a carrier lever individual to each weight; a controlling sleeve movable along the shaft and connected with the levers; a set of helical springs, one for each weight, disposed approximately parallel with said shaft; a member freely adjustable on said shaft while the latter is rotating and with which one end of each spring is connected; and a set of bell-crank levers, one for each weight and bearing

thereagainst at one end, each bell-crank 15 lever being fulcrumed intermediate its ends on a knife-edge bearing and connected at its other end to the other end of the associated spring; the last-named point of attachment of each bell-crank lever being 20 arranged below the fulcrum point of that lever and closer to the shaft than said fulcrum point, and each weight being arranged above the fulcrum of its carrier lever, such relative arrangement remaining constant 25 for all speeds of rotation of the shaft.

In testimony whereof I affix my signature.

JEAN ROMEYN.
